CONCRETE-MIXING APPARATUS

Bernard F. Devine, Milwaukee, and Charles F. Ball, Wauwatosa, Wis., assignors to Chain Belt Company, Milwaukee, Wis., a corporation of Wisconsin

Application September 4, 1936, Serial No. 99,492

12 Claims. (Cl. 259—177)

This invention relates to apparatus for mixing and/or agitating concrete, and more specifically to apparatus for automatically controlling or varying the mixing speed. In order that the precise nature of the invention may be better understood, it may be said that it is well known to those skilled in the art that one factor in the securing of maximum strength in concrete is the mixing of the raw materials for a time sufficient to cause each individual piece of aggregate, both large and small, to be completely coated with the binder—in the case of Portland cement concrete, the cement-and-water paste. To this end, concrete specifications usually require a definite minimum mixing period; and to insure that the operator observes this requirement it is common practice to provide concrete mixing machines with automatic timers, or batchmeters, which may be either manually or automatically set into operation at the proper time, run for the predetermined mixing period, or number of drum revolutions, and then give a visual and/or audible signal to indicate that the batch is completely mixed and may be discharged. In most instances, the discharge mechanism is locked during this mixing period by the batchmeter, or by automatic control mechanism operating in conjunction with it, so that the batch cannot be prematurely discharged; and in some cases, the said discharge mechanism is not only unlocked by the batchmeter or automatic control, but is also actuated by it to automatically discharge the mixture from the mixing chamber. Speed is usually an important factor in concrete mixing and placement, and for this reason it is customary to mix at a relatively rapid rate, and to set the batchmeter for the minimum length of time or number of revolutions of the mixing receptacle necessary to insure complete coating of the aggregates. It is however frequently not feasible or desirable to discharge the batch immediately at the conclusion of the predetermined mixing period, in which case continued agitation at the initial mixing rate is wasteful of power or fuel, with consequent increased cost, and, as has been recently determined, may actually adversely affect the quality and strength of the concrete if continued for considerable time, say more than 45 minutes at accepted mixing speed. If agitation be stopped completely at the end of the mixing period, the mixture—particularly in the case of the wetter mixes—will tend to segregate, with consequent ill effect upon the strength when finally placed; and further, because of the chemical reactions

taking place between the water and the cement, it will start to harden or set. On the other hand, fuel or power can be saved, segregation can be prevented, and setting can be avoided, if the agitation be continued at a comparatively slow rate; and the time for discharging the mixture may be delayed for at least an hour, and in many cases for longer periods, without appreciable effect on the setting or strength qualities of the concrete.

It is one of the principal objects of the present invention to provide a mixing apparatus for concrete and the like, in which the rate of agitation may be automatically changed, at the conclusion of the predetermined minimum mixing period.

It is a further object of the invention to provide a mixing apparatus for concrete and the like, in which the initial mixing may take place for the predetermined minimum mixing period at a relatively rapid rate, at the end of which period the rate will be automatically reduced and the agitation may continue at such lowered rate until discharge, with consequent saving in fuel or power, reduction in costs, and maintainance of the best physical properties in the concrete through prevention of segregation, setting, and over-mixing deterioration.

It is a still further object of the invention to provide a mixing apparatus for concrete and the like, in which a batchmeter or timer is adapted to control a speed changing or regulating instrumentality which in turn determines the rate of agitation, the parts being so arranged that the batchmeter will permit mixing at a relatively rapid rate during the time period or number of drum revolutions for which the batchmeter is set, and at the conclusion of such period the said batchmeter will cause the speed controlling device to automatically reduce the rate of agitation. The mechanism also preferably makes provision for subsequent manual actuation of the speed control instrumentality, so that the speed may be again increased for discharge of the mixture.

With the above and other objects in view, which will appear as the description proceeds, the invention consists in the novel details of construction, and in the novel combinations and arrangements of parts, more fully hereinafter disclosed, and particularly pointed out in the appended claims. While as will be readily appreciated, the invention is susceptible of use with all types of mixers or agitators, including stationary and paving mixers, it has special application to mixers of the truck or transit type, and for pur-

poses of the present disclosure it has been illustrated and will be described in connection with a well known form of such truck or transit mixer.

Referring to the accompanying drawings forming a part of this specification in which like reference characters designate like parts in all the views:—

Figure 1 is a side elevational view of the mixing or agitating unit of a well known form of truck mixer, showing one embodiment of the present invention applied thereto;

Fig. 2 is an enlarged side elevational view, partly broken away, of the essential instrumentalities shown in Fig. 1;

Fig. 3 is a transverse sectional elevational view, taken approximately on the plane indicated by the line 3—3 of Fig. 2, looking in the direction of the arrows; and

Fig. 4 is an enlarged fragmentary elevational view, partly in section, of the operating connections between the batch timer and the speed control instrumentalities.

Referring more particularly to the said drawings, the mixer or agitator unit 5 illustrated therein is of the independent motor driven type and comprises the mixing receptacle or drum 6 mounted for rotation in a suitable framework 7 and adapted to be driven by the motor 8 through the drive shaft 9 and suitable gearing contained in the housings 10 and 11 respectively. The said motor 8 is usually, although not necessarily, of the internal combustion type, in which event it has associated with it the carburetor or fuel mixing device 12 having the usual throttle valve controlled by the arm or lever 13, whereby the speed of the engine may be regulated in the well known manner, which in turn will control the speed of rotation of the mixing drum 6.

A timing device or batchmeter 15 may be mounted upon suitable supports 16. One form of batchmeter which is particularly adapted for use in connection with the present invention is illustrated and described in the prior U. S. Patent No. 2,018,964, granted October 29, 1935, upon an application filed by Rudolph F. Lindow, and such a batchmeter has been illustrated here more or less diagrammatically. It has a driving shaft 17 extending through its casing by means of which power may be supplied to the timing mechanism in any suitable manner. In the present instance, as is best shown in Fig. 2, said shaft 17 is provided with a worm wheel 18 enclosed within a housing 19 and meshed with a worm 20 which is driven by means of a sprocket 21, sprocket chain 22 and sprocket 23, the latter being mounted upon the driving shaft 9 of the mixer unit. The batchmeter 15 may be further provided with a bell or other audible signal device 25, and it also has an arm or lever 26 which is automatically moved back and forth between the full and broken line positions shown in Fig. 4 at the beginning and at the end of a timing cycle. That is to say, at the beginning of the mixing period the arm or lever 26 is moved from the broken to the full line position shown in Fig. 4, which latter position it occupies continuously throughout the pre-determined time period, or number of revolutions of drum 6, and at the conclusion thereof it is automatically moved back to the broken line position.

In order to accomplish the purpose of the present invention suitable connections are established between the batchmeter lever 26 and the arm 13 which actuates the throttle valve, or other speed regulating device of the motor 8, such connec-

tions in the present instance being shown in Figs. 3 and 4 as comprising a link 30, one end of which is connected as at 31 to batchmeter lever 26, and the other end of which is hooked as at 32, for engagement with a pin or roller 33 carried by a manually operable throttle actuating lever 34, pivotally mounted as at 35 on a bracket 36. One end of a rod 37 is connected as at 38 to the lever 34, the other end of said rod being connected to throttle lever 13. The manual throttle actuating lever 34 also carries a pin or roller 40, which, in the "fast" position of the lever, is disengaged from the link 30, as shown in full lines in Fig. 4, but which, as lever 34 is moved to "slow" position, contacts with the surface 41 of the hook 15 portion 32, and raises the link 30 to disengage its hook 32 from the pin or roller 33, as indicated in broken lines in said Fig. 4.

With the parts and instrumentalities arranged as just described, and assuming them to be in the broken line positions illustrated in Fig. 4 just prior to the initiation of a mixing operation, the throttle actuating lever 34 is manually moved to its full line position, thus speeding up the motor 8 and drum 6, and the batchmeter 15 is set into operation, moving its lever 26 and link 30 to their full line positions, and engaging hook 32 with pin or roller 33. When the predetermined mixing time has elapsed, or the drum 6 has made the desired number of revolutions, the batchmeter will automatically return its lever 26 to the broken line position, and through link 30, hook 32, and pin 33, will return the lever 34 to its broken line "slow" position, thus cutting down the speed of motor 8 and drum 6. During the latter part of this movement, the pin or roller 40 will contact the surface 41 of link 30 and raise the link somewhat, so that at the conclusion of the movement the hook 32 will be disengaged from pin 33. This is to permit the lever 34 to be again manually moved to "fast" position without interference from the link 30 or batchmeter, when it comes time to discharge the mixture. It also permits lever 34 to be moved to "fast" position before the batchmeter is started at the beginning of a mixing operation. On the other hand, if the batchmeter be started while the lever 34 is in "slow" position, surface 41 of link 30 will merely ride on pin or roller 40 until hook 32 is in position to drop behind pin 33 should lever 34 be moved to "fast" position.

In order that the batchmeter control may be rendered wholly inoperative if desired, a cam or eccentric 45 is preferably mounted on an extension 46 of bracket 36, and when moved from its full line to its broken line position shown in Fig. 4, will maintain link 30 in its raised broken line position, so that lever 34 may be freely manipulated without interference from the link.

While the mixing unit here illustrated is of the independent motor driven type, it will be immediately obvious that the invention can be as well applied to that type of truck mixer in which the power for rotating the drum 6 is derived through a power take off from the truck traction drive, in which event the linkage 37 will extend to a suitable change speed gearing interposed in the drum drive and independent of the traction gear box.

Therefore while one form of the invention has been illustrated and described, it is obvious that those skilled in the art may vary the precise details of construction and arrangement of the parts without departing from the spirit of the invention, and it is not wished to be limited to the above disclosure except as may be required by the claims.

What is claimed is:

1. In apparatus for mixing concrete and the like, a receptacle; means for inducing agitation of materials in said receptacle at a predetermined uniform rate; means for determining the duration of a mixing period at said rate; and connections between said first and second named means whereby the latter will cause the former to induce agitation at a lower uniform rate after the conclusion of said mixing operation.
2. In apparatus for mixing concrete and the like, a rotatable receptacle; means including a speed regulating instrumentality for rotating said receptacle to induce agitation of materials therein; means for determining the duration of a mixing operation; and connections between said speed regulating instrumentality and said last named means whereby the latter will control the former to cause rotation of said receptacle at a certain uniform rate during said mixing operation, and at a different rate uniform thereafter.
3. In apparatus for mixing concrete and the like, a rotatable receptacle; means including a speed regulating instrumentality for rotating said receptacle to induce agitation of materials therein; means for determining the duration of a mixing operation; and connections between said speed regulating instrumentality and said last named means whereby the latter will control the former to cause rotation of said receptacle at a certain uniform rate during said mixing operation, and at a lower uniform rate thereafter.
4. In apparatus for mixing concrete and the like, a mixing receptacle; a prime mover having a speed regulating device for controlling it; driving connections between said prime mover and receptacle; a batchmeter for determining the duration of a mixing operation, having a member movable at the conclusion of such operation; and connections between said batchmeter member and speed regulating device, whereby the former may cause the latter to reduce the speed of the receptacle subsequent to the mixing operation to a uniform lower rate and maintain such rate indefinitely.
5. In apparatus for mixing concrete and the like, a rotatable mixing receptacle; a prime mover having a speed regulating device for controlling it; driving connections between said prime mover and receptacle; a batchmeter for determining the duration of a mixing operation, having a member movable at the beginning and at the conclusion of such operation; and connections between said batchmeter member and speed regulating device, whereby the former may control the latter to provide for said prime mover driving said receptacle at one uniform rate of speed during the mixing operation, and at a different uniform rate of speed subsequent thereto said latter uniform rate of speed being maintained indefinitely.
6. In apparatus for mixing concrete and the like, a rotatable mixing receptacle; a prime mover having a speed regulating device associated therewith for controlling it; driving connections between said prime mover and receptacle; a batchmeter for determining the duration of a period of mixing, having a member movable at the beginning and at the conclusion of such period; and connections between said batchmeter member and speed regulating device, whereby the former may control the latter to cause a reduction in the rate of agitation at the conclusion of said mixing operation to a uniform value which may be maintained indefinitely.
7. In apparatus for mixing concrete and the like, a receptacle; means for inducing mixing of materials in said receptacle; means for varying the rate of speed of said mixing; means for timing a mixing period; and means controlled by said timing means arranged to cause said speed varying means to induce mixing at one uniform rate of speed during said timed mixing period and at another uniform rate of speed subsequent thereto and to maintain said latter uniform rate indefinitely.
8. In apparatus for mixing concrete and the like, a mixing receptacle; means for inducing agitation of materials in said receptacle; means for controlling the rate of speed of said agitation, manually movable from high to low speed position and vice versa; means for determining the duration of a mixing operation; and connections between said last named means and said manually movable means arranged, should the latter be in high speed position at the termination of said determined mixing operation, to automatically move it to low speed position.
9. In apparatus for mixing concrete and the like, a mixing receptacle; means for inducing agitation of materials in said receptacle; means for controlling the rate of speed of said agitation, including a lever manually movable from high to low speed position and vice versa; a batchmeter for determining the duration of a mixing operation; and lost motion connections between said batchmeter and lever arranged, should the latter be in high speed position at the termination of said determined mixing operation, to automatically move it to low speed position.
10. In apparatus for mixing concrete and the like, a mixing receptacle; means for inducing agitation of materials in said receptacle; means for controlling the rate of speed of said agitation, including a lever manually movable from high to low speed position and vice versa; a batchmeter for determining the duration of a mixing operation; lost motion connections between said batchmeter and lever arranged, should the latter be in high speed position at the termination of said determined mixing operation, to automatically move it to low speed position; and means arranged to temporarily disengage said connections as said lever reaches low speed position to provide for manual movement thereof to high speed position free from batchmeter control.
11. In apparatus for mixing concrete and the like, a mixing receptacle; means for inducing agitation of materials in said receptacle; means for controlling the rate of speed of said agitation, including a lever manually movable from high to low speed position and vice versa; a batchmeter for determining the duration of a mixing operation; lost motion connections between said batchmeter and lever arranged, should the latter be in high speed position at the termination of said determined mixing operation, to automatically move it to low speed position; and means arranged to temporarily disengage said connections as said lever reaches low speed position to provide for manual movement thereof to high speed position free from batchmeter control, said means being also arranged to provide for automatic re-engagement of said connections when the batchmeter is again started.
12. In apparatus for mixing concrete and the like, a mixing receptacle; means for inducing agitation of materials in said receptacle; means for controlling the rate of speed of said agitation,

manually movable from high to low speed position and vice versa; means for determining the duration of a mixing operation; connections between said last named means and said manually movable means arranged, should the latter be in high speed position at the termination of said determined mixing operation, to automatically move it to low speed position; and means

arranged to disengage and maintain said connections ineffective indefinitely, to provide for manual operation of said speed controlling means wholly free from control by said determining means.

BERNARD F. DEVINE.
